UNITED STATES PATENT OFFICE.

GEORGE POLL, OF NEW YORK, N. Y.

CABINET.

1,383,022.

Specification of Letters Patent. Patented June 28, 1921.

Application filed May 28, 1920. Serial No. 384,968.

To all whom it may concern:

Be it known that I, GEORGE POLL, a citizen of the United States, and resident of the city of New York, borough of Queens, 5 in the county of Queens and State of New York, have invented a new and Improved Cabinet, of which the following is a full, clear, and exact description.

In connection with cabinets, and more particularly that type of cabinet used by 10 oculists, it is appreciated that some provision must be made so that the same is capable of receiving a tray, which latter receives the numerous lenses utilized for eye- 15 testing.

With this in mind, numerous attempts have been made to produce a cabinet which shall not be cumbersome in construction, and in which a tray may be provided which 20 shall readily be accessible so that the desired lenses may be withdrawn from the same.

The aforementioned cabinets have for the most part been somewhat cumbersome in 25 construction, and have not been capable of being produced at a low cost. Further, it is often desirable to remove the entire tray for the purpose of cleansing the cabinet and tray, and this has, for the most part 30 been difficult in cabinets heretofore constructed.

With this in mind, I have constructed a cabinet which is ideally adapted for use by oculists, and which shall be capable of receiving a tray, the contents of which may 35 be readily accessible, the entire tray being capable of ready removal for the purpose of cleansing, etc.

Reference is had to the attached sheet of 40 drawings as illustrating one practical embodiment of my invention, and in which drawings;

Figure 1 is an elevational view of a cabinet constructed in accordance with my invention.

Fig. 2 is a plan view of the essential portions of the tray.

Fig. 3 is a sectional side view taken along the lines 3—3 of Fig. 2.

Fig. 4 is an enlarged sectional view taken along the lines 4—4 of Fig. 2, and

Fig. 5 is a bottom plan view of a certain portion of the tray supporting mechanism.

In these views, the reference numeral 55 indicates any suitable type of supporting

legs, to the upper end of which is secured a deck 11 of any desired type. A cabinet 12 extends inwardly from the deck portion 11 and is formed with a suitable recess 13 for a purpose hereinafter more fully specified, the open face of which may conveniently be closed by a door 14. Mounted within the recess 13, or other suitable portion of the cabinet is a bed plate 15.

Mounted upon the upper face, and adjacent to the side edges of this latter element, are track members 16 secured in applied position by any suitable means such as bolts 17. Slidably mounted within the grooves formed in the inner side edges of the track members 16 are rails 18 connected together by means of cross-bars 18' which serve to support a carriage including a pair of uprights 19 connected together at their upper ends by means of a bar 20, such carriage further including horizontally extending side members 21, and a front angle iron 22 for a purpose hereinafter more fully specified.

Now with a view of providing means 80 which will serve to connect the carriage with, and retain the same upon, the rails 18, one of the side rails 21 of the former is conveniently formed, as has been clearly shown in Figs. 2, 3 and 4 with an overlapping portion 23, the edge of the overlapping portion being extended inwardly so as to provide tabs 24 which engage the under side of the rail 18, and retain the carriage in applied position.

The opposite side rail is also formed with an overlapping portion 23, which overlapping portion however, is without the tabs 24 which permits of the carriage being detached from the rails upon this edge being initially swung upward. To normally retain and guide the same however, the lug 25 is pivotally secured, as at 26, to the under side of the rear rail 27 of the carriage, which latter rail extends between the lower 95 ends of the uprights 19. It will be obvious that this tab will serve to normally prevent any movement other than a sliding of the parts, one with respect to the other, it being understood, that by virtue of the pivotal connection of this member, that the same 100 may readily be swung so as to permit of a detachment of the carriage from the rails.

A tray 28, of any desired construction, is now positioned within the carriage, and has 110

its upper edge engaging the bar 20, its lower end resting against and being retained by the angle iron 22. By this construction the tray 28 will be permitted to assume a normally retracted position at which no danger for its contents may be felt, but it will be apparent that the same is instantly available upon the carriage being moved to the position shown in Figs. 2 and 3, at which point the tray 28 may be conveniently removed if this is desired, a detachment of the carriage being effected, as has been indicated, if the operator so wishes.

Obviously numerous modifications of structure might be resorted to without in the least departing from the spirit of my invention, which I claim as—

1. A cabinet, including a bed plate, a pair of track members secured one adjacent each of the side edges of said bed plate, rails slidably associated with said track members, a receiving carriage slidably mounted upon said rails, said carriage presenting a pair of uprights, a rail extending between the lower ends of said uprights, a bar extending between the upper ends thereof, side members having their rear ends secured to said uprights, and an angle iron extend-

ing between and secured to the forward ends of said side members.

2. A cabinet, including a bed plate, a pair of track members secured one adjacent each of the side edges of said bed plate, rails slidably associated with said track members, and a receiving carriage slidably mounted upon said rails, said carriage presenting a pair of side members, one of said side members being formed with an element adapted to positively engage one of said rails, and means associated with the second side member for providing detachable engagement with its associated rail.

3. A cabinet, including a bed plate, a pair of track members secured one adjacent each of the side edges of said bed plate, rails slidably associated with said track members, and a receiving carriage slidably mounted upon said rails, said carriage presenting a pair of side members, one of said side members being formed with an element adapted to positively engage one of said rails, and a pivotally mounted tab associated with the second side member for providing detachable connection with its associated rail.

GEORGE POLL.
